UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

PROTECTIVE DEVICE.

1,142,552.

Specification of Letters Patent.

Patented June 8, 1915.

Application filed January 15, 1914. Serial No. 812,194.

To all whom it may concern:

Be it known that I, EUGENE R. CARICHOFF, a citizen of the United States, residing at Schenectady, county of Schenectady, State of New York, have invented certain new and useful Improvements in Protective Devices, of which the following is a specification.

My invention relates to protective devices for electric circuits, and has for its object the provision of means whereby the application of a higher voltage to the circuit than was intended to be applied, due to carelessness or other causes, is prevented.

My invention relates more specifically to a protective device in connection with electric railway systems designed to operate on different potentials.

Electric railways are common at the present time in which the cars operate at different voltages, say, for instance, at 1200 and 600 volts at different times. In such railway systems it is customary to provide each car with a small generator or dynamotor which when the car is upon a 1200 volt section of line serves to reduce the high voltage of the line to a lower voltage, say 600 volts, for the purpose of supplying the controlling and the lighting circuits of the car. When the car is operating upon a 600 volt section of line the control and lighting circuits are disconnected from the dynamotor and connected directly to the trolley circuit. In an equipment of this kind it is desirable that means be provided for preventing the connecting of the control and lighting circuits to the trolley directly when the latter is operating at high voltage; that is, it is desirable to make it absolutely impossible for the high voltage ever to be applied to these circuits.

One of the objects of my invention is to provide a simple and effective device of this general character which will prevent the occurrence of accidents of the character above described on electric railway lines and in other connections.

In the accompanying drawing in which I have illustrated my invention embodied in concrete form, Figure 1 is a diagrammatic illustration of one form of my invention; and Fig. 2 is a diagram representing a modification thereof.

Referring to the drawings, M and M' represent two motors on the car and C—C

are the master controllers which operate the control circuits. The main controller located in the box D is of the standard and well known form used in equipments of this character and requires no further description. The trolley T has a direct connection with the main controller through the wire 10 and current is supplied to the control circuit through the wire 11. This control circuit is supplied from the motor generator 65 or dynamotor 12 through the wire 13, or is supplied direct from the trolley through the wire 14, depending upon the trolley potential. A switch 15 is provided for changing the connections of the control circuit from 70 the dynamotor to the trolley.

One of the objects of my invention is to prevent the high voltage from being applied to the control circuit in case the operator should neglect to throw the switch 75 15 to the proper position. To this end I provide two electromagnetic switches 16 and 17, having windings connected in series with each other. These two switches are arranged to respond to different current 80 values. In the form of my invention shown in Fig. 1, the switch 16 only responds to a high current value, corresponding to a high potential on the trolley, and does not respond to a low current value. On the other 85 hand, the switch 17 responds to a low current value corresponding to a low potential on the trolley. Switch 17 will also, of course, respond to a high current value. Switch 16 is provided with contacts 18 which 90 when closed by the actuation of the switch, short circuit the winding of the switch 17. The switch 17 when it operates connects the trolley circuit to either the trolley or the dynamotor, depending upon the position of 95 the switch 15. In order to prevent the closure of the switch 17 before the switch 16 gets a chance to short circuit the winding of switch 17, I provide, in the form shown in Fig. 1, a dashpot 19 for delaying the action 100 of the switch 17.

As thus constructed and arranged the operation of the form of device shown in Fig. 1 is as follows: Assuming that the switch 20 is closed and the switch 15 in the position shown in the drawing, connections are made for operation on high voltage. The connection from the trolley is through the switch 20, wire 14, through the contacts on the switch 15 through the dynamotor to 110

ground. There is no circuit from the trolley direct to the control circuit. The control circuit, however, is made through the wire 13 taken from the dynamotor through the contacts on the switch 15, through the windings of switches 16 and 17 in series to ground. The dynamotor is designed to give a low potential, say, for instance, 600 volts, and under these conditions the switch 16 will not operate. The switch 17, however, will operate with an action which is slightly delayed by the dashpot, and will close the connection from the dynamotor to the control-circuit. If, now, the trolley should run on to a 600 volt section, the switch 15 should be thrown to the other position so that a direct connection is made from the trolley to the control circuit through the contacts 21 and 22 on the switch 15. In this case, the switch 17 will operate as before and connect the control circuit direct to the 600 volt trolley. Assume, however, that the trolley is operating upon a 600 volt potential with the switch 15 in the proper position for low potential, that is, with the contacts 21 and 22 in engagement with the segments, and assume that the trolley runs into a 1200 volt section, the operator neglecting to throw the switch 15. Under this condition the 1200 volt trolley will be connected direct to the windings of the switches 16 and 17, but with the arrangement shown this potential of 1200 volts cannot be applied to the control circuit. As soon as high potential is applied to the switch 16 the latter operates and short circuits the winding of the switch 17. Of course, the winding of switch 17 has also high voltage applied to it, and it having been deenergized in passing from low to high voltage starts to operate and close the switch, but since it is retarded by the dashpot in the closure of its contacts, the winding is short circuited by the contacts of switch 16 before it fully closes. The switch 17 will not, therefore, close and voltage will not be applied to the control circuit until the switch 15 is thrown to the proper position. In Fig. 2 I have shown a modification of my invention in which the dashpot is dispensed with. In this case, instead of using the switch 17 I employ a switch 23, which has the peculiar characteristic of being held open when the current is high and closing when the current drops to a predetermined value. This switch is disclosed in the application of Edwin J. Murphy, Serial No. 608,652 filed February 15, 1911, and is now so well known as to require no further description. Otherwise, the arrangement of parts is the same as that shown in Fig. 1. The operation of this form of my invention is as follows: When high voltage is applied to the trolley T, the switch 15 being in

the position shown in the drawing, the dynamotor is connected in circuit and the control circuit is taken from the wire 13 and the contacts of the switch 15, thence through the windings of the switches 16 and 23 in series to ground. Since the dynamotor gives the proper voltage under this condition the switch 23 will operate upon this low current and close a connection from the dynamotor to the control circuit as before. Likewise, when the switch 15 is thrown to the opposite position and the voltage of the trolley is low, the switch 15 being thrown to the proper position the switch 23 will operate to connect the trolley direct to the control circuit. If, however, the trolley should be on the 600 volt circuit with the contacts 21 and 22 of the switch 15 in engagement with the segments and the trolley should run on to a 1200 volt section, the operator neglecting to throw the switch 15, the switch 23 would not operate but will be held in the open position due to the high current. The switch 16 will, however, close and short circuit the winding of the switch 23. Under these circumstances, in order to supply potential to the control circuit it will be necessary to throw the switch 15 to its proper position, whereupon the switch 23 will close to make the proper connection. The arrangement of Fig. 2 accomplishes the same result as that shown in Fig. 1, the difference in the apparatus being that instead of using a switch with a delayed action, as shown in Fig. 1, a switch is used which will not close at all on a high current. It will be seen that I have provided means whereby it is impossible for a higher voltage to be applied to a control circuit than was intended, this being accomplished by very simple and inexpensive apparatus.

While I have described my invention as embodied in concrete form and as operating in a specific manner in accordance with the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:

1. A protective device for electric circuits operating on a plurality of voltages comprising two switches having their windings in series one of which responds to a lower current value than the other, and means whereby the switch which responds to the higher current, in operating, renders the other switch inactive.

2. A protective device for electric circuits operating upon a plurality of voltages comprising two switches having their windings in series one of which responds to a

lower current value than the other, the switch which responds to the higher current short circuiting the winding of the other switch when operated.

- 5 3. A protective device for electric circuits operating upon a plurality of voltages comprising two switches having their windings in series one of which responds to a lower current value than the other, the
- 10 switch which responds to the higher current short circuiting the winding of the other

switch when operated, and means whereby the closure of the switch responding to the lower current value is prevented on high current before its winding is short circuited. 15

In witness whereof, I have hereunto set my hand this 13th day of January, 1914.

EUGENE R. CARICHOFF.
